DIVING BOARD

Raymond Curtis Rude, 2510 Queensberry Road,
Pasadena, Calif.

Filed July 24, 1961, Ser. No. 66,038

Term of patent 14 years

(Cl. D34—5)

FIG. 1 is a perspective view of the diving board showing my new design.

FIG. 2 is a front elevational view of the diving board showing the new design and showing the diving board in dashed lines for convenience of illustration.

I claim:

The ornamental design for a diving board, as shown and described.
